UNITED STATES PATENT OFFICE.

JOHN M. GAMBLE, OF BURLINGTON, IOWA.

WINDOW.

Application filed November 21, 1927. Serial No. 234,751.

This invention relates to ticket windows, and aims to provide novel means whereby a ticket window may be closed and locked against the same being opened from the outside and at the same time affords means to keep out the cold during winter.

An important object of the invention is to provide a device of this character which may be readily moved to its active or closed position and one which may automatically move to its inactive or open position when the lock is operated to release the closure.

A still further object of the invention is to provide a closure of this character which may be readily and easily secured to the window without danger of breaking the window.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view illustrating a ticket window constructed in accordance with the invention.

Figure 2 is a sectional view taken on line 2-2 of Figure 1.

Figure 3 is a transverse sectional view through the closure.

Figure 4 is a fragmental bottom plan view of the closure, and frame in which it is mounted.

Referring to the drawing in detail, the device includes a pair of plates 5 and 6 respectively, the plate 5 constituting the outer plate while the plate 6 constitutes the inner plate.

These plates are provided with inturned edges 7 that are designed to closely engage the glass of which the ticket window is constructed.

Bolts indicated at 8 extend through openings in the outer and inner plates, the bolts being provided with nuts 9 whereby the plates may be secured together, there being provided rubber spacing members 10 for holding the plates in proper spaced relation with each other and at the same time, providing guards for the bolts against which the glass may rest.

The spacing member 10 is disposed ad-

jacent to the upper edge of the frame is elongated as shown by Figure 3 and acts as a stop for the sliding closure 12 when the closure is moved to the limit of its upward movement by the action of the spring 13.

Formed on the inner plate of the closure frame, are guide members 14 in which the closure 12 slides, the guide members being formed of channel material and secured adjacent to the opening in the frame through which the tickets are passed.

Formed integral with the closure 12 is a hook member 15 under which the spring 13 engages, the spring 13 having one end thereof positioned in the tubular support 16 and provided with a coiled portion 17 for lending resiliency to the spring. Thus it will be seen that under normal conditions, the action of the spring 13 is to hold the closure in its inactive or open position.

The hook member 15 is slightly offset defining a shoulder 18 which is engaged by the pivoted latch member 19 supported on the inner surface of the inner plate, the latch member being spring pressed so that the lower end thereof is normally held against the closure 12 with the result that when the closure is moved downwardly to the limit of its closed position, the latch member will find its way into engagement with the shoulder to hold the closure in its closed position.

Should it be desired to move the closure to its open position, it is only necessary to push the upper end of the latch 19 inwardly causing the lower end of the latch member to disengage the shoulder and allowing the spring 13 to act to move the closure to a position as shown by Figure 3.

Formed integral with the closure 12 and extending inwardly therefrom is a flange 20 to be engaged by the fingers of the person selling the tickets and forced downwardly to move the closure to its closed position after a sale has been made.

It will thus be seen that when the closure is moved to its closed position, the latch member will lock the closure in such closed position, to the end that it may only be opened by releasing the latch at the rear of the frame.

I claim:

1. In a device of the class described, a pair of plates having registering openings, a sliding closure operating between the plates, said closures having a hook formed

with an offset portion defining a shoulder, a spring contacting with the hook for urging the closure to its open position, and a pivoted latch member for contacting with the shoulder to lock the closure in its closed position, and bolts passing through the registering openings for securing the plates together.

2. In a device of the character described, 10 a pair of plates having registering openings, means for holding the plates in spaced relation with each other, bolts for securing the plates together, guideways supported between the plates, a closure mounted for sliding movement in the guideways, an elongated spring having one of its ends anchored laterally of the closure, the opposite end of the spring contacting with the closure to normally urge the closure to its open position, 15 a latch member for locking the closure in its closed position, and a flange on the

closure to be engaged by the hand of the operator to move the closure to its closed position.

3. In a device of the character described, 20 a pair of plates, means for securing the plates in spaced relation with each other, a sliding closure operating between the plates, said closure having a hook, a spring having one end thereof disposed under the hook, the 25 opposite end of the spring being anchored to one of the plates, said spring adapted to normally urge the closure to its open position, and a latch member pivotally supported at one of the plates and adapted to engage 30 the closure to lock the closure in its closed position.

In testimony that I claim the foregoing as my own, I have hereto affixed my signature.

JOHN M. GAMBLE.
